UNITED STATES PATENT OFFICE.

ALPHONSO COMSTOCK PRATT, OF MONTCLAIR, NEW JERSEY, ASSIGNOR TO THE FULLER MANUFACTURING COMPANY, OF NEW HAVEN, CONNECTICUT, A CORPORATION OF CONNECTICUT.

PAPER-FEEDING MECHANISM.

1,071,343.

Specification of Letters Patent. Patented Aug. 26, 1913.

Application filed November 7, 1910. Serial No. 590,934.

To all whom it may concern:

Be it known that I, ALPHONSO COMSTOCK PRATT, a citizen of the United States, residing at Montclair, county of Essex, and State 5 of New Jersey, have invented certain new and useful Improvements in Paper-Feeding Mechanism, fully described and represented in the following specification and the accompanying drawings, forming a part of 10 the same.

This invention relates to improvements in paper feeding mechanism.

Considerable difficulty has been experienced in operating feeding mechanisms in 15 connection with high speed printing machines for a reason that the forwarding devices which transfer the sheet from the pile to the front stops or other registering devices necessarily run at such high speeds 20 that the sheet is liable to strike the front stops with such force as to interfere with its register. It has been proposed to overcome this difficulty by the use of what are known in the feeding art as "slow-downs". These 25 slow-down devices are intended to take control of the sheet before it reaches the front stops and slow its speed down to such an extent that the impact of the sheet against the front stops will not be sufficient to interfere with its registration. In certain 30 forms of these slow-down constructions a roll is employed which runs at a constant speed which is considerably slower than the speed of the forwarding devices, the mechanism also including various forms of devices, such, for instance, as a pair of drop 35 rolls, one operating on each margin of the sheet, to enable the slow moving roll to take control of the sheet. These drop rolls, or 40 similar devices, are actuated in such time that the slow moving roll takes control of the sheet after the greater portion of it has passed beyond the slow-moving roll. This 45 slow-down mechanism, after slowing the sheet, releases it when the head of the sheet is some little distance from the front stops and the sheet is then taken control of by the forwarding mechanism and carried against the front stops. This form of slow-down 50 mechanism has not proved satisfactory for various reasons. If, for instance, the sheet happens to be fed from the pile so that one of the forward corners is traveling very slightly in advance of the other corner and 55 goes into the slow-down in this condition,

it will be obvious that one part of the rear edge of the sheet will pass out of the slow-down mechanism before the other part has passed out. The result of this is that when the forwarding mechanism, which is running much more rapidly than the slow-down roll, again takes control of the sheet, it is liable to carry one side of it onward considerably in advance of the other, and, therefore, multiply the feeding error. Certain other difficulties arose in connection with this form of slow-down which it is not necessary to enumerate.

In an attempt to overcome the objections to the form of slow-down mechanism just described, it was proposed to employ a slow-down mechanism comprising a roll extending across and under the sheet pathway with which coöperated a plurality of fixed nipping idler rolls, the under roll and the coöperating rolls nipping and forwarding the sheet. In this form of construction it is obvious that the slow-down rolls must, at the time they take control of the sheet, be driven at the speed at which the sheet is moving, that is, at the speed of the sheet forwarding devices, and that they must not act to slow-down the sheet until the greater portion of the sheet has passed through the slow-down rolls, because it is essential, on account of the speed at which the printing machine is running, that the sheet travel at a high speed between the pile and the front stops. The result of this is that the slowing down of the sheet must take place in a very short period of time, because otherwise sheets could not be fed rapidly enough to the machine. In this form of slow-down mechanism, therefore, it was proposed to drive the roll from what may be termed two sets of driving mechanism, one running at a high speed and the other at a slow speed, and to transfer the control of the roll from the high speed driving mechanism to the low speed driving mechanism at the time it was desired to effect the slowing down of the sheet. This sudden transfer of the control of the slow-down rolls from a driving mechanism running at a high speed to one running at a low speed causes considerable shocks and wear to the operating mechanism, and, further, an appreciable length of time is required for transferring the control of the rolls from one driving mechanism to the other, which amount of time is not con- 110

stant. In other words, under certain conditions of the mechanism, the shift from one driving mechanism to the other may take a longer or shorter period of time than under 5 other conditions. The result of this is that the slow-down mechanism is uncertain in its action and may release the sheet at varying times, or, in other words, at varying distances from the front stops. The sheets, 10 however, are taken from the front stops by grippers or other sheet taking mechanism on the cylinder of the printing machine which cylinder runs at a constant speed. The sheets should arrive at the front stops 15 at the time the grippers are in a predetermined relation to the stops, that is, at the time the grippers are at such a distance from the stops that the time they consume in reaching the stops will be sufficient to 20 permit the proper manipulation of the sheet to bring it into register. In feeding high speed printing machines, the time allowed to effect the register of the sheet is very short. If, therefore, the slow-down mechanism 25 is uncertain in its action and releases the sheet at varying times, there is liability that in some cases the sheet may not reach the front stops in time to enable registration to be effected before the grippers come 30 into position to take the sheet, or may pass the front stops before they are dropped.

It is one of the objects of this invention to produce an improved paper feeding mechanism in which the sheet is forwarded by 35 devices which act positively and certainly, in which the sheet is at all times under proper control, and in which the defects in the feeding action due to uncertainty in operation of the forwarding devices are avoided.

40 A further object of the invention is to produce an improved slow-down for paper feeding machines embodying suitable sheet controlling devices, these devices being operated in such a way that they are certain 45 and positive in their action.

With these and other objects not specifically referred to in view the invention consists in certain constructions, and in certain parts, improvements and combinations as 50 will be hereinafter fully described and then specifically pointed out.

Referring to the accompanying drawings:—Figure 1 illustrates in side elevation so much of a feeding mechanism constructed 55 in accordance with the invention as is necessary to an understanding thereof. Fig. 2 is a plan view of a part of the construction illustrated in Fig. 1. Fig. 3 is a detail view illustrating more particularly in sectional elevation the driving mechanism for a certain slow-down mechanism which may be employed in carrying the invention into effect. Fig. 4 is a detail front elevation of the construction illustrated in Fig. 3. Fig. 60 65 5 is a section on the line 5—5 of Fig. 4. Fig.

6 is a section on the line 6—6 of Fig. 1. Fig. 7 is a detail view.

Referring to the drawings which illustrate one embodiment of the invention, the operative parts of the sheet forwarding construction are supported in a frame comprising side bars 1 pivoted on brackets 2 supported on the printing machine frame 3, the other ends of the bars being supported in the frame 4 which forms a part of the feeder 75 construction.

The cylinder of the printing machine is diagrammatically illustrated at 5, and the front registering devices at 6. In the particular machine shown, the sheet forwarding devices include tapes 7 running over the usual rolls, one of which is indicated at 8. The pile from which the sheets are successively detached is indicated at 9, and the pusher mechanism for detaching the sheets 80 at 10. The pusher mechanism and the tapes are driven from a main shaft 11 which is or may be geared up to the driving mechanism of the printing machine, the movement of this shaft being transmitted to the various 85 agencies driven by it by a train of gears 11'. The parts so far described are well-known in the art, and any other suitable known mechanism for effecting the same purpose may be substituted for them in whole or in 90 part.

Constructions embodying the invention will include sheet forwarding devices by which the sheet is positively and certainly controlled in its passage from the pile to 100 the registering devices. While the particular construction by which the invention is carried into effect may be varied within wide limits, in the construction selected to illustrate the invention the sheet forwarding 105 devices comprise, in addition to the tapes 7, a shaft, as 12, this shaft being provided with collars 13, the shaft and the collars being conveniently termed a roll. The shaft 12 is mounted in brackets 14 mounted on the 110 side frames 1. When this roll is employed in carrying the invention into effect, suitable devices will be used in connection therewith for holding the sheet thereagainst. In the particular machine illustrated, these devices 115 comprise two idler rolls 15 mounted on arms 16 extending from a cross-bar 17, these idler rolls being so arranged that the sheet advanced from the pile by the tapes 7 will, as they reach the rolls, be nipped between 120 them and the roll consisting of the shaft 12 and collars 13. It will be understood that in the construction illustrated this shaft 12 is located beneath the upper run of the tapes and the idler rolls are located above the upper run of the tapes.

In constructions embodying the invention sheets will be advanced at a variable speed, and in constructions embodying the invention in what is considered the best form, this 130

variable speed will be a constantly varying speed. In the construction illustrated for carrying the invention into effect, the shaft 12 is provided with a pinion 18 meshing 5 with a gear 19 loose on a stud 20 supported at one end in a bearing 21 formed on the bracket 14. This stud 20 supports a miter gear 22 in mesh with a miter 23 mounted on a shaft 24 supported at one end in a bracket 10 25 mounted on the stud 20, and at the other end in a bracket 26 carried on a driving shaft 27 operated from the train of gears 11' before referred to, this shaft making one turn for each revolution of the printing 15 machine cylinder. The stud 20 has fast thereon a pinion 28 illustrated as secured thereto by a key 29. The hub of the gear 22 has fast thereto an arm 30 on which is mounted a pinion 31 supported by a screw 20 stud 32. This pinion meshes with the gear 28 and carries a stud 33 on which is mounted a roll 34 engaging in a slot 35 in the gear 19. It is, of course, apparent that as the gear 22 is rotated, the arm 30 will be rotated and 25 will carry the pinion 31 with it, this pinion not only having a rotary movement about the stud 21 but also rotating on its own axis. The pin and roll construction 33, 34 forms a 30 crank for driving the gear 19 and as the position of this crank pin shifts in the slot 35 as the gear 31 rotates and travels, it follows that the gear 19 will be driven at a speed which is not only variable but which is constantly varying, and that this gear 19 acting 35 as a driver will drive the shaft 12 at the same speeds that the driver itself has.

The construction is so arranged that at the time a sheet enters between the rolls 13 and 15, the rolls will be moving at the speed 40 of the carrying tapes 7 and will act to forward the sheet at the speed the sheet had when it entered between them. As the head of the sheet approaches the front guides, however, the rolls are slowed down, so that 45 at the time the sheet emerges from between them it is moving at such a speed that its impact against the front guides will not be sufficient to interfere with its proper registration. It will be observed that the sheet is 50 advanced continuously and at a constantly varying speed, and, furthermore, since these sheet forwarding devices are in continuous engagement with the driving mechanism, there are no sudden shocks or strains put 55 upon the operating parts. It will also be observed that the rolls operate with absolute certainty, there being no error possible, such as is liable to result where a shift has to be made from one driving mechanism to another.

Changes and variations may be made in the construction by which the invention

claimed is carried into effect. The invention is not, therefore, to be confined to the particular construction hereinbefore described and illustrated in the accompanying drawings. 65

What is claimed is:—

1. In a paper feeding mechanism, the combination with sheet forwarding devices running at a constant speed, of a slow down mechanism operating to control the movement of the sheets forwarded by the forwarding devices, said mechanism including devices whereby the slow down mechanism 70 is operated at a speed which varies constantly with respect to the speed of the forwarding devices. 75

2. In a paper feeding mechanism, the combination with a set of constantly running sheet carrying tapes, of a slow down roll located in the tape path, and intermediate the ends thereof, means coöperating with the roll to hold the sheets thereagainst, and means for driving the roll at a speed which 80 varies constantly with respect to the speed of the forwarding devices. 85

3. In a paper feeding mechanism, the combination with a set of constantly running sheet carrying tapes, of a slow down roll 90 located in the tape path and intermediate the ends thereof, and a driving mechanism operating at a speed which varies constantly with respect to the speed of the forwarding devices; with which driving mechanism the 95 roll is continuously engaged.

4. In a paper feeding mechanism, the combination with sheet forwarding devices running at a constant speed, of a slow down roll, means for holding the sheets thereagainst, a driving gear with which the roll is continuously connected, and means including a crank movement operating at varying distances from the center of the gear for driving the gear at a speed varying 100 constantly with respect to the speed of the forwarding devices. 105

5. In a paper feeding mechanism, the combination with a set of constantly running sheet forwarding tapes, of a slow down roll 110 arranged in the tape path and intermediate its ends, means for holding the paper thereagainst, a driving gear with which the roll is continuously connected, a second gear, means for giving the second gear a rotating 115 and traveling movement, and a slot and pin connection between the gears.

In testimony whereof, I have hereunto set my hand, in the presence of two subscribing witnesses.

ALPHONSO COMSTOCK PRATT.
